UNITED STATES PATENT OFFICE

121,197

DESIGN FOR A MORTISE BUTT HINGE

Victor Ramey, Joplin, Mo.

Application April 16, 1940, Serial No. 91,715

Term of patent 14 years

To all whom it may concern:

Be it known that I, Victor Ramey, a citizen of the United States, residing at Joplin, in the county of Jasper and State of Missouri, have invented a new, original, and ornamental Design for a Mortise Butt Hinge, of which the following is a specification, reference being had to the accompanying drawing, forming part thereof.

Figure 1 is an elevational view of a mortise butt hinge embodying my new design;

Figure 2 is a view in side elevation;

Figure 3 is a view in top plan.

I claim:

The ornamental design for a mortise butt hinge, as shown.

VICTOR RAMEY.
